The ornamental design for a thermal pack holding device, as shown and described.

DESCRIPTION

FIG. 1 is a perspective view of a thermal pack holding device showing my new design;

FIG. 2 is a top plan view thereof;

FIG. 3 is a bottom plan view thereof;

FIG. 4 is a front elevation view thereof;

FIG. 5 is a side elevation view thereof; and,

FIG. 6 is a perspective view of a thermal pack holding device placed on a person's chest.

The broken lines showing of the thermal pack holding device in FIGS. 1 through 6 are for the purpose of illustrating portions of the article and form no part of the claimed design. The broken line showing of the human figure and pillow in FIG. 6 is for the purpose of illustrating environment and forms no part of the claimed design.
